UNITED STATES PATENT OFFICE.

JOHN MUTH, OF NORWALK, CONNECTICUT, ASSIGNOR TO THE E. H. HOTCHKISS COMPANY, OF NORWALK, CONNECTICUT, A CORPORATION OF CONNECTICUT.

STAPLE-DRIVING MACHINE.

Application filed March 24, 1921. Serial No. 455,121.

To all whom it may concern:

Be it known that I, JOHN MUTH, a citizen of the United States, residing at Norwalk, county of Fairfield, State of Connecticut, have invented an Improvement in Staple-Driving Machines, of which the following is a specification.

This invention relates to stapling machines, and more particularly to that type known as strip staple machines, wherein each staple, at the time it is driven, is severed from a strip of integrally connected staples which is fed forwardly at each operation of the machine to bring the staples successively into position to be severed and driven.

In a machine of this type, as usually constructed, the staple strip is fed forward to the point where the individual staples are severed and driven by feeding and holding devices which are located inside the machine casing and are inaccessible from the exterior of the latter, said devices holding the strip against backward movement and making its impossible to retract the same.

It is not uncommon, however, for the staples to become clogged in the machine from various causes, and in such event it is desirable to retract and remove the strip in order to clear the machine.

The present invention has, therefore, for its primary object to provide means accessible from the exterior of the machine casing for disengaging the feeding and holding devices from the staple strip in order to permit the strip to be withdrawn from the machine.

With the foregoing and other objects in view, I have devised the novel mechanism which I will now describe, reference being had to the accompanying drawing forming a part of this specification and in which:

Fig. 1 is a longitudinal vertical section of a complete stapling machine having applied thereto a preferred form of the invention.

Fig. 2 is a transverse section taken substantially on the line 2—2, Fig. 1.

Fig. 3 is a perspective view, on an enlarged scale, of the staple carrying bar and the pawl releasing slide.

Fig. 4 is a side elevation, on a reduced scale, of the complete machine.

Fig. 5 is an enlarged detail side elevation of the staple carrying bar, the detent and

feed pawls, and the pawl releasing slide, illustrating the mode of operation of the latter.

Fig. 6 is a perspective view of a modified form of releasing slide.

10 denotes the machine base, which is provided at its forward end with an anvil 48 having the usual concave clenching recess 11. Pivoted to said base is the head of the machine, which comprises a casing 12 having at its lower side a longitudinal recess 14 in which is located a staple carrying bar 15 upon which the staple strip slides, said bar being secured to the casing by pins 16 and being pivoted at 13 between upstanding ears 49 at the rear end of the base 10. The bar 15 is centrally located in the recess 14, and the upper portion thereof is spaced from the lateral walls of said recess by plates 17 interposed between said bar and walls in order to provide the necessary clearance for the free passage of the staple strip. At its forward end the casing 12 is formed with a vertically disposed cylindrical enlargement to constitute a guide 18 for a vertically reciprocating plunger 19 having a knob or hand piece 20 at its upper end. A coil spring 21 is interposed between the hand piece 20 and the top of the guide 18, said spring normally holding the plunger in raised position. The flat, forward end of the bar 15 is disposed in substantial alinement or in substantially the same vertical plane with the flat, rear face of the plunger 19, only sufficient clearance being provided between said bar and plunger to permit the latter to pass the former and to cooperate therewith to shear off the first staple of the strip when the plunger is depressed. The staple strip 50 is supported and slides on the top of the bar 15 with its foremost staple normally projecting beyond the end of the bar in a position to be severed from the strip by the plunger 19 in its downward movement and driven through the throat 22 of the machine upon the anvil 48.

23 denotes a cam plate pivoted at 25 within the casing 12 at the rear of the plunger 19 and having pivoted at its lower end a feed pawl 26 formed with a forked lower end to engage between the individual staples of the strip. The cam plate 23 is oscillated on its pivot 25 at each reciprocation of the plunger 19 by a lug 27 on said plunger which engages lower and upper cam surfaces

28 and 29 formed on said cam plate, said cam surfaces being so designed that at each oscillation of the cam plate 23 the feed pawl 26 will be moved a distance corresponding 5 to the width of one staple on the strip. When the plunger 19 is depressed, engagement of the lug 27 with the cam surface 28 causes the feed pawl 26 to move backwardly upon the staple strip, and, when said plunger is raised, engagement of said lug with the cam surface 29 causes said feed pawl to be moved forwardly to advance the strip. 10 30 denotes a detent pawl pivoted at 31 within the casing and having a forked lower end 15 to engage the staple strip 50 and prevent retrograde movement of the latter when the feed pawl 26 is moved backwardly thereon. 32 denotes a spring carried by a pin 24 within the casing and having end portions engaging 20 the pawls 26 and 30 respectively to hold said pawls in yielding engagement with the staple strip.

The parts thus far described constitute an illustrative example of a well known type 25 of stapling machine which, specifically, may be of any usual or desired construction and arrangement. In such a machine the staple strip is usually inserted from the rear and is moved forwardly along the bar 15 until 30 the foremost staple is brought to a position beneath the plunger 19, said strip being thereafter held against rearward movement and withdrawal from the machine by the pawls 26 and 30, which are held in constant 35 engagement therewith by the spring 32. Should the machine, however, become clogged for any reason, it becomes desirable to withdraw the strip, and, in order to permit this, to release or disengage the 40 pawls 26 and 30, which, however, in machines of this type as usually constructed, are permanently secured within the casing and are inaccessible from the exterior thereof. To this end, in accordance with the 45 present invention, the following means are provided.

The plates 17 are made of sufficient thickness to provide a clearance between the bar 15 and the walls of the recess 14 in excess of 50 that required for the reception of the staple strip 50, and in this additional space is arranged a sliding channel member 33 having the edges of its side flanges resting on said plates 17, said member overlying and straddling the bar 15 and staple strip 50 and being movable longitudinally thereon. The sliding member or slide 33 constitutes an auxiliary guide for the staple strip, which lies between it and the bar 15, and facilitates 55 the free movement of said strip inasmuch as it serves to hold the latter out of contact with the walls of the recess 14 which, being parts of the casting constituting the casing 12, are relatively rough. The rear end of 60 the slide 33 projects through and extends be-

yond the rear of the casing 12, being formed with a finger piece 35 for convenience in handling. The forward end of the slide 33, when the latter is in its normal position as shown in full lines in Fig. 1 and in dotted lines in Fig. 5, lies in the rear of the pawls 26 and 30 in all positions of said pawls, and, therefore, does not interfere with the normal operation of the latter. Said slide is held in this position by a coil spring 42 located in a recess 41 formed in the casing 12 and communicating with the longitudinal recess 14. The spring 42 surrounds a struck up tongue 40 on the top web of said slide and engages at its opposite ends respectively the front walls of the recess 41 and a shoulder 34 on said tongue, thereby holding said shoulder in engagement with the rear wall of said recess. The spring 42 and slide 33 are assembled in the casing 12 prior to the insertion and attachment of the staple carrying bar 15, which thereafter holds the tongue 40 in the recess 41 and retains said slide in permanent position in the machine, so as to prevent the same from being removed and mislaid. 38 denotes an opening formed in the slide 33 adjacent the forward end thereof, and 39 an opening in the side wall of the casing 12 communicating with the recess 14 and with which said opening 38 is adapted to register when the slide 33 is moved into its forward position.

In operation, when it is desired for any reason to remove the staple strip, the slide 33 is pushed forwardly by means of the finger piece 35, causing the forward end thereof to engage the pawls 26 and 30 and lift the same out of engagement with said strip, as shown in full lines on Fig. 5. The strip may then be withdrawn from the rear of the machine if long enough to project therefrom, or may be caused to slip back and drop out of the machine by tilting the latter, being freed or started, if necessary, by inserting a suitable implement through the openings 38 and 39 and pushing said strip backwardly.

In Fig. 6 is illustrated a modified form of pawl releasing slide comprising a channel member similar to the member 33 and like the latter adapted to straddle the bar 15 and staple strip and to fit the space between said bar and the walls of the recess 14, said member 45 being also provided with a finger piece 35 and an opening 38. The member 45 is intended to be removed from the machine when not in use and may be employed in connection with any number of like machines, its operation being otherwise similar to that of the member 33 as above described.

Having thus described my invention I claim:

1. A pawl releasing device for strip staple machines comprising a channel member adapted to slide above the staple strip and

- engage the feed and detent pawls of the machine.
2. A pawl releasing device for strip staple machines comprising a sliding channel member having an opening adjacent one end and a finger piece at the opposite end.
3. In a stapling machine comprising a casing and devices within said casing for feeding and holding a staple strip, means independent of the feeding and holding devices and accessible from the exterior of said casing for releasing said feeding and holding devices to permit withdrawal of said strip.
4. In a stapling machine, in combination, a casing, a staple strip carrying bar, staple strip feeding devices within said casing and comprising a feed pawl and a detent pawl, and means independent of the feeding and holding devices and accessible from the exterior of the casing for disengaging said pawls from the strip to permit the latter to be withdrawn from the machine.
5. In a stapling machine, in combination, a casing, a staple strip carrying bar, staple strip feeding and holding devices within said casing, and a member slidable on said bar and accessible from the exterior of said casing for disengaging said feeding and holding devices from the staple strip to permit withdrawal of the latter.
6. In a stapling machine, in combination, a casing, a staple strip carrying bar, staple strip feeding and holding devices within said casing and a channel member slidable on said bar and accessible from the exterior of said casing for disengaging said feeding and holding devices from the staple strip to permit withdrawal of the latter.
7. In a stapling machine, in combination, a casing, a staple strip carrying bar, staple strip feeding and holding devices within said casing, and a sliding channel member adapted to straddle said bar and the staple strip thereon and accessible from the exterior of said casing for disengaging said feeding and holding devices from the staple strip to permit withdrawal of the latter.
8. In a stapling machine, in combination, a casing having a recess, a staple strip carrying bar in said recess, staple strip feeding and holding devices within said casing, and a sliding member between said bar and the walls of said recess and accessible from the exterior of the casing for disengaging said feeding and holding devices from the staple strip to permit withdrawal of the latter.
9. In a stapling machine, in combination, a casing having a recess, a staple strip carrying bar in said recess, staple strip feeding and holding devices within said casing, and a sliding channel member disposed between said bar and the walls of said recess and accessible from the exterior of said casing for disengaging said feeding and holding devices from the staple strip to permit withdrawal of the latter.
10. In a stapling machine, in combination, a casing, a staple strip carrying bar, staple strip feeding and holding devices within said casing, and a sliding member projecting through the rear of said casing for disengaging said feeding and holding devices from the staple strip to permit withdrawal of the latter.
11. In a stapling machine comprising a casing and devices within said casing for feeding and holding a staple strip, staple strip guiding means accessible from the exterior of said casing and movable to disengage said feeding and holding devices from the staple strip and permit withdrawal of the latter.
12. In a stapling machine comprising a casing and devices within said casing for feeding and holding a staple strip, means independent of the feeding and holding devices and accessible from the exterior of said casing for releasing said feeding and holding devices to permit withdrawal of said strip, and means for retaining said releasing means within said casing.
13. In a stapling machine, in combination, a casing having a recess, a staple strip carrying bar, staple strip feeding and holding devices within said casing, and a member slidable on said bar and accessible from the exterior of said casing for disengaging said feeding and holding devices from the staple strip to permit withdrawal of the latter, said member having a tongue extending into said recess and retaining said member in said casing.
14. In a stapling machine comprising a casing and devices within said casing for feeding and holding a staple strip, means accessible from the exterior of said casing for releasing said feeding and holding devices to permit withdrawal of said strip, said means being independent of and separate from the feeding and holding devices, and means for normally holding the releasing means in inoperative position.
15. In a stapling machine, in combination, a casing, a staple strip carrying bar, staple strip feeding and holding devices within said casing, a member slidable on said bar and accessible from the exterior of said casing for disengaging said feeding and holding devices from the staple strip to permit withdrawal of the latter, and a spring co-operating with said slidable member for normally holding the same out of engagement with said feeding and holding devices.
16. In a stapling machine, in combination, a casing having a recess, a staple strip carrying bar, staple strip feeding and holding devices within said casing, a member slidable on said bar and accessible from the exterior of said casing for disengaging said feeding and holding devices from the staple strip to permit withdrawal of the latter.

- of said casing for disengaging said feeding and holding devices from the staple strip to permit withdrawal of the latter; said member having a tongue extending into said recess and retaining said member in said casing; and a spring in said recess and engaging said tongue for normally holding said member out of engagement with said feeding and holding devices.
17. In a stapling machine, in combination, a casing having a longitudinal recess and a second recess communicating therewith, a staple strip carrying bar in said longitudinal recess, staple strip feeding and holding devices within said casing, a sliding channel member disposed between said bar and the walls of said longitudinal recess and straddling said bar and the staple strip thereon, said member being accessible from the exterior of said casing and being movable to engage said feeding and holding devices and disengage the same from said staple strip to permit the withdrawal of the latter, and said member having a tongue extending into said second recess and retaining said member in said casing, and a spring in said last named recess and engaging said tongue for normally holding said member out of engagement with said feeding and holding devices.
18. In a stapling machine, in combination, a casing having a recess and an opening communicating with said recess, a staple strip carrying bar in said recess and spaced from the walls thereof, staple strip feeding and holding devices within said casing, and a sliding channel member accessible from the exterior of said casing for engaging said feeding and holding devices and disengaging the same from the staple strip to permit withdrawal of the latter, said member being located between said bar and the walls of said recess and straddling said bar and the staple strip thereon and having an opening adapted to register with the opening in said casing when said member is moved to release said feeding and holding devices.
19. In a stapling machine, in combination, a casing having a longitudinal recess, staple strip carrying bar in said recess, spacing plates interposed between said bar and the walls of said recess, staple strip feeding and holding devices within said casing, and a sliding channel member adapted to straddle said bar and a staple strip thereon and having its edges resting on said plates, said member being accessible from the exterior of said casing and being movable to disengage said feeding and holding devices from the staple strip to permit withdrawal of the latter.
20. In a stapling machine, in combination, a casing, a staple strip carrying bar, a staple strip feeding device within said casing, and a member slidable on said bar and accessible from the exterior of said casing for disengaging said feeding device from the staple strip to permit withdrawal of the latter.
21. In a stapling machine, in combination, a casing, a staple strip carrying bar, a staple strip feeding device within said casing, and a channel member slidable on said bar and accessible from the exterior of said casing for disengaging said feeding device from the staple strip to permit withdrawal of the latter.
22. In a stapling machine, in combination, a casing, a staple strip carrying bar, a staple strip feeding device within said casing, and a sliding channel member adapted to straddle said bar and the staple strip thereon and accessible from the exterior of said casing for disengaging said feeding device from the staple strip to permit withdrawal of the latter.
23. In a stapling machine, in combination, a casing, a staple strip carrying bar, a staple strip feeding device within said casing, and a sliding member projecting through the rear of said casing for disengaging said feeding device from the staple strip to permit withdrawal of the latter.
24. In a stapling machine comprising a casing and a device within said casing for feeding a staple strip, staple strip guiding means accessible from the exterior of said casing and movable to disengage said feeding device from the staple strip and permit withdrawal of the latter.
- In testimony whereof I affix my signature.
- JOHN MUTH.
